SUCTION CLEANER

David L. Glass, North Canton, Ohio, assignor to
The Hoover Company, North Canton, Ohio, a
corporation of Ohio

Application March 9, 1936, Serial No. 67,885

6 Claims. (Cl. 15—183)

This invention relates to suction cleaners in general and more particularly to new and novel improvements in agitating means for a suction cleaner. More specifically the invention comprises an improved brush and brush mounting construction for a suction cleaner agitator.

The modern suction cleaner cleans by air and by surface agitation. The surface agitation is commonly obtained by use of a rotary agitator embodying rigid beater elements and flexible brush elements. These brush elements gradually wear down with use and necessitate either replacement or adjustment. A preferred type of agitator embodies a brush element which is reversible to compensate for bristle wear. Springs are provided in the agitator brush seat which retain the brush element at its maximum radial extension. In the second or worn brush position the spring will be more expanded resulting in a different and reduced spring pressure upon the brush element. This variation in spring pressure is undesirable and often results in a loose, noisy brush. In the agitator constructed in accordance with the present invention, the new and novel brush and brush seat arrangement prevents difference in spring pressure with the brush in its reversed position.

It is an object of the present invention to provide a new and improved suction cleaner.

30 It is another object of the invention to provide a new and improved agitator for a suction cleaner.

A still further object of the invention is to provide a new and improved rotary agitator embodying adjustable brush elements.

Still another object is the provision of an agitator comprising a brush seat in which is seated a brush element which is spring-pressed into working position.

40 Still another object is the provision of a rotary agitator for a suction cleaner in which is provided a brush seat adapted to seat reversibly a removable brush element which is so constructed that spring pressure upon the brush element is constant in all of its positions.

These and other more specific objects will appear upon reading the following specification and claims, and upon considering in connection therewith the attached drawing to which they relate.

50 Referring now to the drawing in which a preferred embodiment of the present invention is disclosed:

Figure 1 is a front view of a suction cleaner constructed in accordance with the present inven-

tion with a portion of the nozzle wall broken away and showing an agitator embodied therein;

Figure 2 is a partial longitudinal cross section through an agitator constructed in accordance with the present invention showing the removable and reversible brush element;

Figure 3 is a view similar to Figure 2 but with the brush element in the reversed position;

Figure 4 is a view in perspective of the brush element per se.

Referring again to the drawing, a modern suction cleaner is illustrated in which the body of the machine comprises a main casting 1 which includes a nozzle 2 and a motor casing 3 and is movably supported upon wheels 4—4 etc. A 15 pivoted handle 5 provides means by which the user can propel the machine. Within the body of the cleaner are various working parts characteristic of this type of machine but which do not directly relate to the present invention. 20 There is, however, a fan chamber 6 therein which houses a suction creating fan 7 carried by the rotatable motor shaft 8 which extends downwardly through the fan chamber. Within the nozzle 2, in a common and well known manner, is positioned a rotary agitator 9 which is suitably connected to the shaft 8 by a power-transmitting belt 10.

Agitator 9 comprises a hollow cylindrical body 11 rotatably mounted upon a longitudinally extending through-supporting shaft 12 and formed centrally with a reduced pulley surface 13. The ends of body 11 are protected by stationary thread guards, of which one is indicated at 14, carried by the stationary shaft 12.

Upon the surface of the agitator 9 is provided a rigid longitudinally extending rigid beater element 15 and circumferentially spaced from this element are one or more brush-seating channels 16 each of which is adapted to seat removably a 40 brush element. The opposite ends of each channel 16 are open, the top of the inner end in each case being defined by a shoulder or stop 17a while the outer end in each case is defined by a central shoulder or stop 17b and two side shoulders 17c, 45 only one of the shoulders 17c being shown in Figures 2 and 3. The height of shoulder 17a is midway between shoulders 17b and 17c.

Within the channel is seated a brush comprising a rigid back 18 in which are mounted flexible bristles 19. The back also is provided at its opposite ends with shoulders, a narrow shoulder at one end being indicated at 20 and a wider and lower shoulder at the opposite end being indicated at 21.

The difference in height between brush shoul-

ders 20 and 21 is equal to the difference between shoulders 17a and 17b, or 17a and 17c.

When the brush is new and the bristle length is maximum, the unit should be positioned within 5 its seat 16 as illustrated in Figure 2, that is, with the shoulder 20 underlying shoulder 17a. The shoulder 21 at the opposite end of the brush back from shoulder 20 is seated under the lower shoulders 17c. When so positioned the brush back 10 is level and is spaced from the bottom of channel 16 being urged upwardly, or radially outward, against the contacted shoulders 17a and 17c by the two arms 23 and 24 of a flat leaf spring 22 which extend longitudinally of the channel.

Between its ends and on its under side brush back 18 is provided with a downwardly extending shoulder or abutment 25 positioned a short distance from its outer end, with the brush in its new brush position, and with a second downwardly extending shoulder or abutment 26 exactly at its opposite or inner end. These abutments have a height equal to one half the difference in height between shoulders 17b and 17c. That is, equal to the difference in height between 25 shoulders 20 and 21. Arm 24 of the leaf spring is curved upwardly beyond abutment 25 as illustrated in Figure 2 so that the two arms of the spring 22 contact the brush back 18 at the same distance above the bottom of the brush channel 30 and at the sides of the abutments described.

With the brush in the reversed, or worn brush position, as illustrated in Figure 3, shoulder 21 seats under seat shoulder 17a while narrow shoulder 20 extends up under central shoulder 17b. 35 Each end of the brush has moved radially outward one-half the distance separating shoulders 17b and 17c. In this new position the extremities of the spring arms 23 and 24 contact the bottom of abutments 25 and 26 of the brush back. As 40 the height of each abutment is equal to the increment by which the brush has been raised or moved radially outward in the channel, it is obvious that the spring arms 23 and 24 are in the same position and are flexed to the same extent as in the new brush position illustrated in 45 Figure 2.

The brush back may be channeled centrally on its under side, as illustrated in Figure 4, in which event the abutments 25 and 26 are in 50 reality a pair of spaced abutments. They function as single abutments, however, for the spring arms 23 and 24 extend across the brush back and contact both sides of each abutment.

The removable brush element is inserted in the 55 agitator channel, removed from the channel, and again inserted in the reversed position, in a manner common to this type of agitator. To accomplish this operation it is necessary only to depress one end of the brush back by means of a tool, 60 such as a screw driver, urge it longitudinally of the channel whereupon the opposite end of the brush back becomes disengaged from the overlying shoulder or stop of the channel and moves outwardly permitting the entire removal of the brush. The insertion of the brush is exactly the 65 reverse operation.

I claim:

1. In combination, a body having an elongated seat, a surface cleaning element removably positioned in said seat and adapted to be reversed 70 end for end, pairs of cooperating stops so posi-

tioned on said body and element as to vary the extension of said element from the bottom of said seat in the reversed positions, spring means urging said element to retain said pair of stops in contact, and abutments on said element to contact said spring means in one position of said element. 5

2. In combination, a body having an elongated seat, a surface cleaning element removably positioned in said seat and adapted to be reversed end for end, means upon said body and element to determine the extension of said element from the bottom of said seat, said element extending to different points in the reversed positions, spring means urging said element against said means and toward or from which said element is movable, and abutments upon said element so positioned as to contact said spring in one position to compensate for the movement of said element from said spring upon reversal and to maintain substantially the force exerted by said spring means. 10 15 20

3. In combination, a body having an elongated seat, a surface cleaning element removably positioned in said seat and adapted to be reversed end to end to vary the height of said element from the bottom of said seat, means determining the position of said element in said seat in the reversed positions, resilient means contacting said element and urging the latter outwardly in said seat, said element being spaced at different distances from said resilient means in the reversed positions but being so contoured as to effect contact with said resilient means at substantially the same levels in the reversed positions. 30 35

4. In combination, a body having an elongated seat, a surface cleaning element adjustable in said seat to vary the extension of said element relative to said body, spring means urging said element outwardly relative to said body, said element being positioned closer to, or farther from, said spring means upon adjustment, said element being formed with spring-contacting surfaces of different extensions so contoured as to contact said spring means at the same height 45 in said seat to effect a constant deflection in said spring in the various positions of said element.

5. In combination, a body having an elongated seat, a surface contacting removable element adapted to be seated reversibly end for end in 50 said body, spring means on said body contacting said element at spaced points, and spring-contacting surfaces formed on the underside of said element and adapted to contact said spring means in reversed positions of said element and 55 of such extensions as to maintain constant force-characteristics in said spring means.

6. In a suction cleaner rotary agitator, a body, an elongated brush seat in said body, spring means in the bottom of said seat, a brush element including a reversible end for end rigid back seated in said seat and prevented from displacement by overlying means on said body, said back being positioned at different heights in said seat in the reversed positions, and spring means 60 contacting portions at different heights on said back adapted to contact selectively said spring means in the reversed positions of said brush to maintain constant spring force on said back. 65
